United States Patent Office

Des. 188,529
Patented Aug. 9, 1960

188,529

PILLOW

Livia Szamosi, Los Angeles, Calif., assignor of one-third to Andrew P. Solt and George Solt, both of Los Angeles, Calif.

Filed Mar. 21, 1960, Ser. No. 59,799

Term of patent 14 years

(Cl. D3—9)

FIG. 3.

Fig. 1 is a top plan view of a pillow showing my new design;

Fig. 2 is a bottom plan view; and

Fig. 3 is a cross section taken on the broken line 3—3 of Fig. 1.

I claim:

The ornamental design for a pillow, as shown.
